UNITED STATES PATENT OFFICE.

CHARLES T. WITTSTEIN, OF CHICAGO, ILLINOIS.

DESIGN FOR A FINGER-RING.

SPECIFICATION forming part of Design No. 36,619, dated November 10, 1903.

Application filed December 2, 1901. Serial No. 84,478. Term of patent 14 years.

To all whom it may concern:

Be it known that I, CHARLES T. WITTSTEIN, a citizen of the United States, residing at Chicago, in the county of Cook and State of Illinois, have invented a new, original, and ornamental Design for a Finger-Ring, of which the following is a specification, reference being had to the accompanying drawings, forming a part hereof.

10 Figure 1 is a view in side elevation of my new, original, and ornamental design for a finger-ring; Fig. 2, an edge elevational view thereof, and Fig. 3 a plan view thereof.

What I regard as new, and desire to secure by Letters Patent, is—

15 The ornamental design for a finger-ring, as shown.

In testimony whereof I have signed my name to this specification in the presence of two subscribing witnesses.

CHARLES T. WITTSTEIN.
